UNITED STATES PATENT OFFICE.

CHARLES L. TRAVIS, OF MINNEAPOLIS, MINNESOTA, ASSIGNOR OF ONE-HALF TO ALONZO T. RAND, OF SAME PLACE.

TOY.

SPECIFICATION forming part of Letters Patent No. 239,125, dated March 22, 1881.

Application filed February 24, 1881. (No model.)

To all whom it may concern:

Be it known that I, CHARLES L. TRAVIS, of Minneapolis, in the county of Hennepin and State of Minnesota, have invented certain Improvements in Toys, of which the following is a specification.

The object of my invention is to produce an instrument upon which a child may cut his teeth, and which will also form an attractive and amusing toy.

My device consists in a rattle having a smooth metal body of an oblatespheroidal form, provided on the edge with a handle containing a whistle.

Referring to the accompanying drawings, Figure 1 represents a face view of the device, and Fig. 2 a longitudinal central section of the same on the line *x x* of Fig 1.

A represents the body of the rattle, made of sheet metal, with a smooth outer surface, in an oblate spheroidal form, and of such size that it can be readily introduced into a child's mouth. Within the body there are shot or equivalent loose pieces of metal, to rattle about therein, as in the ordinary rattles in general use. On one side the body is provided with a handle, B, the end of which contains a whistle, C.

The instrument constructed as above forms an attractive toy, combining a rattle and a whistle, and, owing to the form and position of the body, it serves as an excellent surface for the child to bite upon when teething. The form and position of the body create an impulse on the part of the child, when holding the handle, to introduce the body into his mouth, and this fact it is that gives to the device its value.

The whistle may be omitted, if desired.

I am aware that metal rattles have been made in many forms, and in some instances provided with rattles; and I am also aware that hard and soft bodies answering no other purpose have been made in various forms for children to cut their teeth upon, and I lay no claim thereto.

I am aware that watches and imitation toy watches have been made in a circular flattened form with a small ring holding knob on one side, and this I do not claim, an essential and distinctive feature of my device being the long rigid handle extended from the side of the body in the manner shown, so that it may be, and naturally will be, grasped by a child, and that when thus grasped it will present the body in position to enter the child's mouth.

What I claim as my invention is—

1. A toy for a child's use, consisting of a smooth metallic body of oblate spheroidal form, adapted to enter the child's mouth, and a handle extended outward rigidly from one side of the body, as described and shown, as a means by which the child may hold the device and introduce the body into his mouth.

2. The combined toy consisting of the smooth metal body of oblate spheroidal form, adapted to enter the child's mouth, and provided with the rigid side handle and the internal loose shot.

3. The combined whistle and rattle having the smooth body of the peculiar form described and shown.

CHARLES L. TRAVIS.
